SIGURD L. WALSOE, OF SPRINGDALE, CONNECTICUT, AND LAWRENCE J. BETZ, OF ASTORIA, NEW YORK, ASSIGNEES TO REMINGTON TYPEWRITER COMPANY, OF ILION, NEW YORK, A CORPORATION OF NEW YORK

COMPUTING MACHINE

Application filed September 18, 1930. Serial No. 482,744.

Our invention relates to computing machines and more particularly to automatically operating means for aligning the totalizer wheels and removing any spiraling that may 5 occur therein.

The main object of our invention, generally stated, is to provide simple, inexpensive, and effective means of the character specified.

A further object of our invention is to provide means of the character referred to which 10 are embodied in and carried by the traveling and detachable totalizers of a computing machine, or a combined typewriting and computing machine.

A still further object of our invention is to provide simple and effective means of the character specified which may be readily embodied in existing machines without modifying, or materially modifying, the existing 15 structural features of said machine.

To the above and other ends which will hereinafter appear our invention consists in the features of construction, arrangements of parts and combinations of devices set forth 20 in the following description and particularly pointed out in the appended claims.

In the accompanying drawings, wherein like reference characters designate corresponding parts in the different views:—

Fig. 1 is an enlarged, detail, fragmentary, 25 fore and aft vertical sectional view of a portion of a machine embodying our invention, the parts being disposed in the normal position.

Fig. 2 is a like skeletonized view of the same with some of the parts omitted and representing the parts in the actuated position.

Fig. 3 is an enlarged, detail front view of 30 one of the totalizers shown detached and with parts broken away and in section.

Fig. 4 is a perspective view of devices, shown separated and detached, added by our present invention for automatically aligning 35 wheels in the totalizers.

Fig. 5 is an enlarged, detail top plan view of one of the totalizers shown detached and with parts broken away.

Fig. 6 is an enlarged, detail, fragmentary 40 side view of a portion of one of the totalizers

showing the pivoted end of the aligning bar and the bearing therefor.

Fig. 7 is an enlarged, detail, sectional view taken through the axis of the carrier wheels and showing the manner of mounting the control lever for the aligning bar. 55

Fig. 8 is an enlarged, detail, fragmentary, skeletonized, vertical sectional view of a totalizer taken on the line 8—8 of Fig. 5 and looking in the direction of the arrows at said 60 line.

We have shown our invention in the present instance embodied in a No. 23 Remington accounting machine in which the devices of the present invention may be readily incorporated without modifying, or materially modifying, the structural features of said machines as they now exist. It should be understood however that the invention is not restricted to embodiment in such machines but 65 may be embodied in accounting and combined typewriting and accounting machines generally, wherever found available. 70

So much of the #23 Remington accounting machine as is disclosed in the present instance 75 is similar to that shown in the patent to Wahl 1,270,471, dated June 25, 1918.

In the accompanying drawings the usual supporting bar 1 is connected to the typewriter carriage to travel therewith in the 80 usual manner and supports a plurality of so-called vertical totalizers, only one of which is shown, that being designated as a whole by the reference numeral 2. Each totalizer comprises two parallel side plates 3 united by 85 suitable cross bars and provided with bearings for various shafts and spindles 4, 5, 6, 7, 8 and 9 for various of the totalizer wheels control levers, etc., as will hereinafter more 90 clearly appear. The shaft 9 has a pair of hook-like locking latches 10 and 11 fixed thereto (see Fig. 1) and adapted to engage over a dove tail portion 12 of the carrying bar to detachably hold the companion totalizer on said bar. An arm 13 extends from the latch 11 and terminates outside of the 95 totalizer in a finger piece 14 by which the latches may be released.

The latch 11 also is provided with a locking dog 15 adapted to enter into interdental 100

spaces between teeth 16 of a rack bar 17 secured to the supporting bar 1 and thus prevent a displacement of the companion totalizer along said bar. The spaces between the teeth of the rack are at letter space intervals corresponding to the letter space movement of the typewriter carriage and the carrying bar 1 connected therewith. Each of the side plates 3 of each totalizer is provided with a hook-like engaging member 18 adapted to engage under the dove tail portion 19 of the supporting bar 1 to further secure the totalizer in place on said supporting bar. A contractile returning spring 20 is connected at one end to a member 21 supported on the spindle or pivot rod 8, whereas the opposite end of said spring is connected to a pin 22 on the inner side of the latch arm 11. The force of the spring 20 is exerted to hold the latch members 10 and 11 in the engaging position, as shown in Fig. 1. When the finger piece 14 is depressed, the latches are released and the totalizer may be detached or adjusted along the supporting bar 1.

We avail ourselves of the latching means just described and certain of the parts controlled thereby for controlling the aligning means of our present invention, as will hereinafter clearly appear.

Each vertical totalizer in addition to the parts mentioned above includes a series of number wheels 23 mounted to turn on the spindle or shaft 4 and adapted to expose the numbers 24 thereon through a sight opening 25 in the cover or housing 26 of the totalizer. Each number wheel 23 has a toothed gear 27 fixed thereto which meshes with a companion intermediate toothed gear 28 loosely mounted on the shaft 5. Each intermediate gear 28 in turn meshes with a toothed carrying wheel 29 loosely mounted on the shaft or spindle 6.

In addition to the foregoing construction there is contained in each totalizer 2 the usual transfer mechanism for transferring the tens from one denomination to another and embodying the locked Geneva gear train comprising the Geneva star wheels 30 and 30^a, pinions 31 on opposite sides of and fixed to each of them, cooperative Geneva members 32 one fixed on a side of each of the carrying wheels 29 except that for the highest order and having depressions 33 in the periphery thereof, and three wide carrying teeth 34 on each of the carrying wheels 29 except that for the highest order and which coat with a companion gear 31 on one side of the associated Geneva wheel 30, all as indicated in Fig. 1.

It is not deemed necessary to further describe this usual transfer mechanism except to point out that the Geneva wheels 30 and 30^a are arranged in two rows or series and that each of the wheels 30, and its attached gears 31, is carried by and pivoted to turn on a shiftable lever 35 or 36, sometimes called the

"stop rocker arms". The levers 35 are all pivoted in alignment to turn on the spindle or pivot rod 8, whereas the levers 36 are all pivoted in alignment on the spindle or pivot rod 7. Each of the Geneva wheels 30 of one series is pivoted at 37 on a lever 35, whereas each of the Geneva wheels 30^a of the other series is pivoted at 38 on a lever 36. A pivotal movement of any of the levers 35 and 36 from normal position is effective to disengage the wheels 30 and 31 carried thereby from the associated wheels or members with which they coat, as shown in Fig. 2.

The means by which such pivotal movement is transmitted to each of the levers 35 and 36 will now be described, as well as the effect thereof on the locking bar or so-called "safety bar" to be hereinafter described.

The lower ends of the levers 35 and 36 are arranged in transverse alignment at letter space intervals and each of them is bifurcated at 39 to receive a master dog 40 controlled from the actuating mechanism for vibration fore and aft of the machine, as will presently appear. The letter space movements of the carriage, and the totalizer 2 connected therewith, advances the lower ends of the levers 35 and 36 successively into cooperative relation with the master dog 40 as the totalizer is carried through the computing zone. An operation of the actuation mechanism at any of these intervals will result in operating the lever 35 or 36 in cooperative relation with the master dog, as shown in Fig. 2. This will result not only in disengaging the wheels of the transfer mechanism, as previously pointed out but in actuating the "safety bar" to move it to locking position where it will coat with the remainder of the levers 35 and 36 and prevent a movement thereof from normal position.

Thus, the locking bar 41 is pivoted at its ends, as at 42, to the side plates 3 of the totalizer for swinging movement from the ineffective Fig. 1 position, to the effective Fig. 2 position. The bar 41 extends throughout the width of the totalizer above the upper forwardly projecting ends of the levers 35 and 36, each of which is provided with an engaging portion 43 and a contact or cam 44. When the locking bar 41 is shifted to the locking position, indicated in Fig. 2, the engaging edge 45 of the bar will overlie all of the engaging portions 43 of the levers 35 and 36, except the one that has been actuated, and prevent an operation thereof. The movement of the locking bar 41 from the ineffective to the effective position is brought about by the contact 44 on the actuated lever 35 or 36 engaging said bar and swinging it to the Fig. 2 position.

When the actuated lever 35 or 36 is released for return movement to normal position under control of its spring 46 or 47 respectively, the locking bar 41 will be returned to nor-

mal position by an independent spring 48. Referring particularly to Fig. 8 it will be seen that one end of the spring 48 is anchored on a bar 49, whereas the opposite end of said 5 spring is connected to a pin 50 carried by an arm 51 pivoted to turn freely on the spindle or pivot rod 7 and preferably is located about midway in the length thereof, as indicated in Fig. 5. The free end portion 52 of 10 this arm (see Fig. 8) contactively engages the upper side of a lug 53 riveted at 54 to the locking bar 41 and normally maintains said locking bar in the Figs. 1 and 8 position; the terminal portion of the arm 52 working 15 in a cut-out or slot 55 in the locking bar. The arm 51 usually carries a wedge shaped tooth 56 that coacts with the teeth of one of the middle carrying wheels 29 to align it at each actuation of the arm 51.

20 So much of the mechanism as has been thus far described constitutes part of the well known Remington accounting machine, as does the actuating mechanism, a description of which is to follow. We have availed 25 ourselves of this mechanism in the present instance to actuate and control the aligning means of the present invention, which we will now describe.

On the left-hand end of the shaft or spindle 30 6 there is mounted to turn freely a controlling lever 57 of the first order. The rear end of this lever is provided with an opening 58 greater than a semi-circular portion of a disk-like end 59 of a link 60 that is seated in said 35 opening. The upper end of this link is pivoted at 61 to one end of the locking bar 41 and is received in a cut-out in an end of the bar. The forward end of the lever 57 is pivoted at 62 to an aligning member or bar 63 40 and constitutes a support for the bar at one end thereof. The opposite end of the aligning bar is shaped as represented in Figs. 3 and 6. From these figures it will be seen that the right-hand end of the aligning bar is reduced in height to provide a shoulder 64 that 45 is adapted to bear against the inner face of the right-hand side plate 3 of the totalizer, whereas the reduced end 65 of the bar is received in a bearing opening 66 in the said 50 side plate so that the bar may receive a pivotal movement therein from the full to the dotted line position shown in Fig. 3 and vice versa. The shape of the bearing opening 66 corresponds to the shape of the reduced end 55 65 of the bar, so that the parallel side walls of the opening will permit the said pivotal movement of the bar but will prevent it from turning on its longitudinal axis, thus maintaining the aligning bar with its upper round- 60 ed edge uppermost in a position to engage between the teeth of the intermediate gears 29, as shown in Figs. 1 and 3, to align them. The bar 63 is prevented from moving axially in one direction by the shoulder 64 bearing 65 against the associated side plate 3, whereas said bar is prevented from axial movement in the opposite direction by the lever 57 which coacts therewith. From an inspection of Fig. 3 it will be understood that the bar 63 is preferably so shaped that the upper aligning 70 edge thereof will never coact with say, the two right-hand wheels 28 of the lowest orders but in its movement from the dotted to the full-line position in Fig. 3 will be brought 75 successively into engagement with the remainder of said wheels 28, beginning with the lower order wheel and ending with the higher order wheel to align them progressively from right to left. It will be understood that ordinarily there is little or no spiraling in the 80 lowest order wheels, such spiraling when it does occur being progressively greater as the highest order wheel is approached. For this reason, and for the additional reason that the machine as usually constructed is provided with the aligning device 56 hereinbefore described, and also is provided with means for automatically aligning the lowest order wheel, as will presently appear, there 85 is no necessity of the bar 63 coacting with the two lowest order wheels. The main advantages of our present construction is in automatically aligning the highest order wheels where the spiraling is greatest, and especially 90 in comparatively wide totalizers of from, say, ten or more wheels capacity. This spiraling in the highest order wheels if permitted to remain is apt to result in injury to the machine, for reasons which will hereinafter more 95 clearly appear.

From what has been said it will be understood that each operation of the usual key controlled actuating mechanism will result in operating the master dog 40, which in turn 100 will move the particular lever 35 and 36 with which the master dog is in cooperative relation at the instant, as indicated in Fig. 2. It follows that this movement will be transmitted to the locking bar 41 and from 105 said bar through the link 60 and lever 57 to the aligning bar 63, moving the latter from the normal, engaged, position shown in full lines in Fig. 3, to the released, dotted line position shown in said figure. This operation 110 takes place before the master wheel 67 is actuated to turn the particular carrying wheel 29 which, at the time, is in mesh therewith and before any of the wheels controlled by the carrying wheel in question can be actuated, as will presently more fully appear. 115 When the actuated lever 35 or 36 is free to return to normal position, the locking bar 63 will be returned to effective position by the spring 48 (Fig. 8), thereby moving the aligning bar 63 to the effective, full line, position 120 shown in Fig. 3, thereby aligning all of the wheels 28 controlled by the aligning bar and all of the other wheels controlled by the wheels 28. The effect of this is to normally 125 hold and maintain substantially all of the 130

wheels of each totalizer aligned and locked against accidental displacement by aligning means contained in and carried by such totalizer, and to automatically displace such aligning means on the particular totalizer that is in the computing zone at each operation of the key controlled actuating means and before motion is transmitted to any of the wheels therein by the master wheel or device 67.

We will now refer to the usual key controlled actuating means, sufficient only of which is shown to arrive at an understanding of our present invention.

15. Each numeral key of the machine is connected through a link 68 with a so-called fan 69 that turns freely on a fixed shaft 70 carried by the frame of the actuator. Each fan 69 in addition to full stroke mechanism, 20 which need not be described, has associated therewith a gooseneck 71 that turns on the shaft 70 and is arranged beside its companion fan 69. Each fan receives a preliminary movement independently of the associated gooseneck, due to the pin and slot connection 69^a, 69^b between them. Each fan 69 has a cam 72 that coacts with a universal bar 73 carried by arms 74 fixed to a universal shaft 75. Said shaft 75 carries an arm 76 to which 25 one end of a link 77 is pivoted, the opposite end of said link being operatively connected to a master cam 78 that controls the master dog 40 to move it from the Fig. 1 to the Fig. 2 position and vice versa, as hereinbefore described. When such movement takes place, a rearward extension or truck lock 79 on the master dog engages between the teeth of a rack 80 fixed on the supporting bar 1, as shown in Fig. 2, and locks the carriage 30 against movement.

This same movement of the universal shaft 75 is effective to withdraw a master pawl 81 (see Fig. 1) from engagement with the teeth of the master wheel 67, and by which 35 the master wheel is properly aligned and normally held against rotation. The master pawl 81 is carried by or forms part of a master cam plate 82 pivoted at 83 on the actuator frame and provided with a cam slot 84 therein. A pin 85 is carried by an arm 86 fixed on the universal shaft 75. Said pin coacts with the cam 84 to withdraw pawl 81 from engagement with the teeth of the master wheel 67 against the force of a spring 50 87 by which the master pawl 81 is forced into engagement with and aligns the master wheel. These movements take place and are completed at the first part of the down stroke of the key and before the upper wall 55 of the slot 69^b reaches the companion pin 69^a and actuates the associated gooseneck 71.

Fig. 2 represents the position of the parts when the last mentioned actuation has taken place and before the companion gooseneck 65 has started to actuate the master wheel 67,

as will presently more clearly appear. It will be seen that at this time the aligning bar 63 of the totalizer in the computing zone has been moved out of engagement with the intermediate wheels 28 and is held free from such engagement, so as not to interfere with the movement of any of such wheels during the turning of the master wheel.

As a continued depression of the actuated key takes place the associated gooseneck will be moved, and through the cam 88 thereon operating on a pin 89 carried by arms 90 on a sector shaft 91, will rock said shaft an extent determined by the particular key depressed. The sector shaft 91 carries a toothed sector 92 which is engageable with a pinion 93 operatively connected with the master wheel 67 to turn the latter.

During this period the master dog 40 and the aligning bar 63 remain in the position shown in Fig. 2 due to the fact that the dwell 72^a on the actuated cam 72 coacts with the universal bar 73. When, however, the cam 72 has passed the universal bar at about the completion of the movement of the master wheel, the universal bar will be freed from control of the cam and the master dog and aligning bar 63 will return to the normal position, shown in Fig. 1, where said aligning bar will engage the wheels 28 and align all of the wheels in the totalizer, or all of those controlled by the aligning bar 63.

From an inspection of Fig. 8 it will be seen that the usual fixed aligning cam or member 94 is secured at 95 to the actuator frame 96 and is located adjacent to the master wheel 67 at the right-hand side thereof, or behind the master wheel as the parts appear in Fig. 8. The purpose of this member 94 is to automatically align wheels 29 in each totalizer 105

2 as the latter is traveling with the carriage from right to left to and past the master wheel, thereby preventing injury to teeth of the wheels 29 and the master wheel. This ordinarily will correct slight lack of proper alignment of the wheels 29 especially in totalizers having a smaller capacity. However, as the wheels of the highest order have the greatest amount of spiraling, when spiraling exists, and these highest order wheels 110 are the first to meet the member 94 in the movement of the carriage from right to left, the teeth of the wheels 29 are, ordinarily, at times apt to be injured or broken by said member 94. This is especially true when totalizers of considerable capacity are employed, say totalizers having ten or more wheels and the spiraling up to the extent of half the width of a tooth is involved in the wheels 29 of the highest order. It will be understood that by our invention this difficulty is overcome as the wheels in each totalizer are always maintained in alignment by the aligning bar 63 until the wheels 29 of the highest order have passed the fixed 115 120 125 130

10 It will be understood that an important factor in attaining the above mentioned results is the fact that each aligning bar 63 is carried by its totalizer and normally engages the wheels and is only released therefrom 15 when the associated totalizer is in the computing zone and an operation of the actuator takes place.

It also will be seen that we have provided very simple yet highly effective means for 20 attaining the results specified and that in embodying the devices of our invention in the Remington accounting machine it is unnecessary to modify, or materially modify, existing structural features thereof.

25 While the anti-spiraling devices of this invention are shown in the present instance applied to the vertical totalizers 2 it will be understood that they are also applicable in a like manner to the cross totalizer disclosed 30 in said Wahl patent and embodied in said Remington accounting machine.

It will be borne in mind that in said patent and machine the universal shaft 75 disclosed herein is coupled to a corresponding shaft for 35 the cross totalizer, and that the remaining parts beyond said shaft for the cross totalizer are the same as those disclosed herein.

Various changes may be made in the construction without departing from our invention 40 as it is defined in the accompanying claims.

What we claim as new and desire to secure by Letters Patent, is:—

1. The combination of a carriage, a totalizer 45 mounted to travel with the carriage and including a series of gear wheels, key controlled actuating mechanism for said totalizer carried by the frame of the machine, aligning means carried by said totalizer and normally and successively engaging a plurality of adjacent gear wheels therein for 50 aligning them and removing any spiraling thereof that might occur, and automatically operating means controlled by each operation of said key controlled actuating mechanism when said totalizer is in the computing zone for releasing said aligning means from said wheels.

2. The combination of a carriage, a totalizer 55 mounted to travel with the carriage and including a series of gear wheels, key controlled actuating mechanism for said totalizer carried by the frame of the machine, a shiftable aligning bar carried by said totalizer and operative successively on and nor-

70 mally engaging a plurality of said gear wheels for aligning them and removing any spiraling that might occur, and automatically operating means controlled by each operation of said key controlled actuating mechanism when the totalizer is in the computing zone for shifting said aligning bar out of engagement with said wheels.

3. The combination of a carriage, a totalizer 75 mounted to travel with the carriage and including a series of gear wheels, key controlled actuating mechanism for said totalizer carried by the frame of the machine, an aligning bar carried by said totalizer and mounted to turn on a fixed pivotal center at one end of the bar and to be brought successively into engagement with a plurality of said gear wheels to align them, means for normally maintaining said locking bar in engagement with said wheels, and automatically operating means controlled by each actuation of said key controlled actuating mechanism when the totalizer is in the computing zone for releasing said aligning bar from engagement with said wheels.

4. The combination of a detachable traveling totalizer including a series of gear wheels, an aligning bar carried by and detachable with said totalizer and normally engaging and aligning said series of wheels, key controlled actuating mechanism for said totalizer carried by the frame of the machine, and means operable at the actuation of a key of said actuating means when the totalizer is in the computing zone for disengaging the aligning bar from said wheels before rotation of any of the wheels can be effected.

5. The combination of a detachable traveling totalizer including a series of gear wheels, aligning means carried by and detachable with said totalizer and operative successively on said series of gear wheels to align them and normally maintained in engagement therewith to hold them in alignment, key controlled actuating mechanism including a master dog actuated at each operation of a key of said mechanism, and means controlled by said master dog when the totalizer is in the computing zone for releasing said aligning means from said wheels.

6. The combination of a detachable traveling totalizer including a series of gear wheels, aligning means carried by and detachable with said totalizer and operative successively on said series of gear wheels to align them and normally maintained in engagement therewith to hold them in alignment, a locking bar carried by the totalizer and shiftable to and from locking position, operative actuating connections between said locking bar and said aligning means, key controlled actuating mechanism on the frame of the machine, and means controlled thereby when the totalizer is in the computing zone for actuating said locking bar at each operation of a key.

7. The combination of a detachable traveling totalizer including a series of gear wheels, aligning means carried by and detachable with said totalizer and operative successively on said series of gear wheels to align them and normally maintained in engagement therewith to hold them in alignment, a locking bar carried by the totalizer and shiftable to and from locking position, operative actuating connections between said locking bar and said aligning means for disengaging the latter from said wheels when the locking bar is shifted to locking position, key controlled actuating mechanism including a master dog actuated at each operation of a key of said mechanism, and means controlled by each operation of said master dog when the totalizer is in a computing zone for shifting said locking bar to locking position and for releasing the aligning means from said wheels.

8. The combination of a detachable traveling totalizer including a series of gear wheels, aligning means carried by and detachable with said totalizer and operative successively on said series of gear wheels to align them and normally maintained in engagement therewith to hold them in alignment, said aligning means comprising an aligning bar pivoted at one end directly on the frame of the totalizer, a lever carried by said totalizer and to which the opposite end of the aligning bar is connected, key controlled actuating means on the frame of the machine, and means controlled thereby when the totalizer is in the computing zone for actuating said lever at each operation of a key.

9. The combination of a detachable traveling totalizer including a series of carrying wheels, a series of number wheels, and a series of intermediate gear wheels in mesh with said number wheels and said carrying wheels; aligning means carried by and detachable with said totalizer and operative successively on said intermediate gear wheels to align them, said aligning means comprising an aligning bar pivoted at one end, a controlling lever mounted to turn on the axis of said series of carrying wheels and connected to the other end of said aligning bar; and key controlled actuating mechanism carried by the frame of the machine and including means operable at each actuation of a key thereof when the totalizer is in the computing zone for moving said controlling lever.

10. The combination of a detachable traveling totalizer including a series of carrying wheels, a series of number wheels, a series of intermediate gear wheels in mesh with said number wheels and carrying wheels, and a movable locking bar; aligning means carried by and detachable with said totalizer and comprising an aligning bar pivoted at one end and operative successively on said intermediate gear wheels to align them, a controlling

lever mounted to turn on the axis of said series of carrying wheels and connected to the other end of said aligning bar, and a link intermediate said movable locking bar and said controlling lever; and key controlled actuating mechanism on the frame of the machine including means for actuating said locking bar at each operation of a key of said actuating mechanism when the totalizer is in the computing zone.

11. The combination of a detachable traveling totalizer including a series of carrying wheels, a series of number wheels, a series of intermediate gear wheels in mesh with said number wheels and carrying wheels, a series of transfer-wheels, and a series of levers by which said transfer-wheels are carried; aligning means carried by and detachable with said totalizer and comprising an aligning bar cooperative with one series of said wheels successively to align them, and means controlled by an actuation of any one of said transfer-wheel carrying-levers for actuating said aligning bar; and key controlled actuating mechanism carried by the frame of the machine and including means for shifting one of said transfer-wheel carrying-levers at each operation of a key of such mechanism when the totalizer is in the computing zone.

12. The combination of a detachable traveling totalizer including a series of carrying wheels, a series of number wheels and a series of intermediate gear wheels in mesh with said number wheels and carrying wheels; aligning means carried by and detachable with said totalizer and comprising an aligning bar pivoted at one end and operative successively on said intermediate gear wheels to align them, a controlling lever mounted to turn on the axis of said series of carrying wheels and connected to the other end of said aligning bar, and a link intermediate said movable locking bar and said controlling lever; key controlled actuating mechanism on the frame of the machine including a master dog actuated at each operation of a key of said actuating mechanism; and means controlled by said master dog when the totalizer is in the computing zone for actuating said controlling lever.

13. The combination of a detachable traveling totalizer including a series of carrying wheels, a series of number wheels, a series of intermediate gear wheels in mesh with said number wheels and carrying wheels, a series of transfer-wheels, a series of levers by which said transfer-wheels are carried, a shiftable locking bar moved into locking position in cooperation with the remainder of said transfer-wheel carrying-levers when any one of them is moved from normal position; aligning means carried by and detachable with said totalizer and comprising an aligning bar cooperative with one series of said wheels successively to align them, operative connec-

tions between said locking and aligning bars for moving the aligning bar out of effective position when the locking bar is moved to effective position; and key controlled actuating mechanism including means operable on one of said transfer-wheel carrying-levers at each actuation of a key when the totalizer is in the computing zone.

14. The combination of a detachable traveling totalizer including a series of carrying wheels, a series of number wheels, a series of intermediate gear wheels in mesh with said number wheels and carrying wheels, a series of transfer wheels, a series of levers by which 15 said transfer wheels are carried, a shiftable locking bar moved into locking position in cooperation with the remainder of said transfer-wheel carrying-levers when any one of them is moved from normal position; aligning means carried by and detachable with 20 said totalizer and comprising an aligning bar cooperative with one series of said wheels successively to align them, operative connections between said locking and aligning bars 25 for moving the aligning bar out of effective position when the locking bar is moved to effective position; and key controlled actuating mechanism carried by the frame of the machine and including a master dog actuated 30 at each operation of a key of said actuating mechanism, said master dog being operable on one or another of said transfer-wheel carrying-levers when the totalizer is in the computing zone and effecting a disengagement 35 of the aligning bar preliminary to a rotation of any of the wheels in the totalizer.

Signed at Stamford, in the county of Fairfield and State of Connecticut, this 17th day of September, A. D. 1930.

1,837,599.—*Sigurd L. Walsoe, Springdale, Conn., and Lawrence J. Betz, Astoria, N. Y.*
COMPUTING MACHINE. Patent dated December 22, 1931. Disclaimer filed May 4, 1933, by the assignee, *Remington Typewriter Company*.

Hereby enters this disclaimer to that part of the claim in said patent which is in the following words:

“4. The combination of a detachable traveling totalizer including a series of gear wheels, an aligning bar carried by and detachable with said totalizer and normally engaging and aligning said series of wheels, key controlled actuating mechanism for said totalizer carried by the frame of the machine, and means operable at the actuation of a key of said actuating means when the totalizer is in the computing zone for disengaging the aligning bar from said wheels before rotation of any of the wheels can be effected.”
